UNITED STATES PATENT OFFICE.

WILLIAM J. LEARY, OF CHICAGO, ILLINOIS.

BLACKBOARD-ERASING APPARATUS.

Application filed October 26, 1922. Serial No. 596,961.

To all whom it may concern:

Be it known that I, WILLIAM J. LEARY, a citizen of the United States, residing at Chicago, in the county of Cook and State of Illinois, have invented new and useful Improvements in Blackboard-Erasing Apparatus, of which the following is a specification.

This invention relates to an apparatus or device for cleaning a blackboard, such as are commonly used in schools and on which the exercises are written by means of chalk.

As is well known, the cleaning of such boards is attended with risks to the health of the teachers and scholars, inasmuch as considerable dust is developed during the cleaning of the boards which is not only inhaled by the persons standing near the board and is therefore unsanitary, but is also objectionable on account of this dust being deposited on the clothes of the persons and on the books, furnishings and furniture in the room.

It is the object of this invention to produce an apparatus for cleaning or erasing the chalk from the blackboard in such a manner that the dust will be carried away from the blackboard the instant the same is generated, thereby rendering the cleaning operation more sanitary and avoiding pollution of the atmosphere.

A further object of the invention is to provide means for accomplishing this purpose which can be easily manipulated by persons unskilled with mechanical devices and will operate efficiently without liability of getting out of order.

A further object of the invention is to provide an apparatus of this character which can be produced at comparatively low cost and which can be installed in class rooms without employing expensive extra equipment.

In the accompanying drawings:

Figure 1 is a perspective view of the complete blackboard eraser forming part of the cleaning apparatus which is constructed in accordance with my invention. Figure 2 is a vertical longitudinal section of the same. Figure 3 is a horizontal longitudinal section thereof taken on line 3—3, Fig. 2. Figure 4 is a horizontal section taken on line 4—10, Fig. 2, looking downwardly. Figure 5 is a fragmentary sectional perspective view of a partition between the gathering chamber and the equalizing chamber of the brush.

Figure 6 is a horizontal section taken on line 6—6, Fig. 2. Figure 7 is a fragmentary sectional perspective view of one end of the dust loosening means of the blackboard eraser. Figures 8 and 9 are vertical transverse sections taken on the correspondingly numbered lines in Fig. 2. Figure 10 is a horizontal section taken on line 4—10, Fig. 2, looking upwardly. Figure 11 is a fragmentary bottom plan view of one end of the brush. Figure 12 is a vertical cross section, on an enlarged scale, of one portion of the dust loosening means, showing the manner of attaching a brush strip to the supporting plate or head. Figure 13 is a fragmentary vertical longitudinal section taken on line 13—13, Fig. 12. Figure 14 is a fragmentary vertical transverse section, on an enlarged scale, taken on line 14—14, Fig. 6. Figure 15 is a fragmentary sectional perspective view of one end of the brush, showing a modified form of the means for attaching the rubbing strips to the supporting plate or head. Figure 16 is a perspective view, showing the manner of installing one or more erasers on a blackboard in accordance with my invention. Figure 17 is a fragmentary vertical longitudinal section of the means mounted on the rail of a blackboard for the purpose of removing any accumulated dust on the blackboard eraser. Figure 18 is a horizontal section of the same taken on line 18—18, Fig. 17. Figures 19 and 20 are vertical cross sections taken on the correspondingly numbered lines in Fig. 16.

Similar characters of reference indicate corresponding parts throughout the several views.

The blackboard eraser proper forming part of my improved apparatus for cleaning blackboard comprises a dust loosening means or brush, means for creating a vacuum and sucking the dust away from the dust loosening means, and a hand-operated valve mechanism whereby the suction effect upon the brush may be controlled at will.

The details of the brush embodying these features may be varied, but the preferred form of the same shown in Figs. 1—14, is constructed as follows:

The dust loosening brush preferably comprises a rectangular border which has two longitudinal strips 30, 30, and two transverse strips 31 connecting opposite ends of the longitudinal strips, and a plurality of longitudinal intermediate strips 32 arranged

lengthwise within the border, these several strips being constructed of felt or other fibrous material and the same being separated from each other by intervening passages 33 extending from the outer front surface of the same to the rear or inner side of these strips.

- These several strips which form the dust loosening members of the brush, may be supported at their rear or inner edges by a support of any suitable construction but preferably by means of a sheet metal supporting plate 34 which latter is secured to the inner edges of these strips and provided with a plurality of slots 35 which correspond with the passages formed between the several strips, so that the dust-laden air which is generated during the operation of cleaning a blackboard may pass through these several passages of the brush from the front to the rear side of the same. In the preferred construction of the means for attaching the rear or inner ends of these strips with the metal supporting plate, a longitudinal bead 36 is formed on the strip supporting plate in rear of each intermediate longitudinal strip and a similar bead 37 is formed on this supporting plate in rear of each of the transverse strips of the border, as best shown in Figs. 1, 6, 8, 9 and 12. Each of these strips of the brush is provided in its rear side with a longitudinal groove 38 which receives the respective bead, and forms flanges 39 on the inner side of each strip on opposite sides of the respective bead. Each of these flanges is firmly attached to the adjacent part of the metal supporting plate by engaging one side of each of these flanges with claws or prongs 40 which are bent out of the stock of the adjacent bead and into the respective surface of the strip flange while the opposite side of this strip flange is engaged by a plurality of prongs or claws 41 which are formed on the adjacent edge of a slot in the supporting plate and engage with the corresponding upright side of the respective flange on one of the strips, as best shown in Figs. 2, 7, 8, 9 and 12-14. A firm hold of the supporting plate is thus obtained upon the several felt strips of the brush which permits of vigorously rubbing the felt strips over the surface of the blackboard without liability of loosening the strips.
- Instead of providing the strip supporting plate with beads which indent the rear surfaces of the strips, as shown in Figs. 2, 7, 9 and 12, this supporting plate may be provided with backwardly-projecting ribs or beads 42, as shown in Fig. 15, which last-mentioned beads merely serve to stiffen or strengthen this supporting plate without assisting in attaching strips to the supporting plate.
- The brush is mounted on a holder which

contains the valve mechanism whereby the suction through the brush is controlled, which holder in its preferred forms is constructed as follows:

43 represents a plate of sheet metal arranged at the back of the brush but separated therefrom by an intermediate gathering chamber or space 44 and also provided with a plurality of openings 45, so that the dust-laden air passing through the several passages between the strips, may enter the gathering chamber and escape through the openings in the plate 43 of the brush holder. This plate 43 is arranged within the flange 46 arranged at the lower edge of the outer shell 47 of the enclosing casing and is provided with an outwardly-projecting flange 97 which is secured to the inner side of the flange 46 of the enclosing casing by brazing. The inner side of the brush is spaced apart from the plate 43 by spacing lugs or projections 48 on the marginal parts of the perforated plate 43, so that the same engage the marginal parts of the strip supporting plate, as best shown in Figs. 2, 8 and 9, and thus maintain these plates a predetermined distance apart while they are assembled. The brush is removably held within the flange 47 of the partition or inner wall plate 43 by providing the front end of the latter with an inwardly-turned hook 49 which engages with the shoulder formed by the foremost claws and the front end of the brush, while the shoulder formed by the claws on the rear transverse edge of the brush is engaged by means of a catch 50 having a hook-shaped lower end engaging with the last mentioned shoulder while the upper end is pivoted by means of a pin 51 to the rear part of the enclosing casing. This catch is constantly turned by means of a spring 52 in the direction for engaging this hook with the rear transverse shoulder of the brush, so that the same tends constantly to hold the latter in place within the gathering chamber. Disengagement of the catch 50 with the rear shoulder of the brush may be effected by means of a fingerpiece 53 arranged on the outer side of this catch, as shown in Figs. 1 and 2.

In order to avoid marring furniture and parts of the blackboard with which the marginal part of the brush may come in contact, a protecting strip or bumper 54 of rubber or similar material is secured between the inner edge portions of the flange 46 on the enclosing casing and the adjacent flange 97 of the perforated partition, as best shown in Figs. 2, 8, 9 and 14.

In order to draw the dust-laden air not only through the longitudinal passages between the strips of the brush, means are provided for also carrying away any dust which may gather on the outer sides of the border strips, for which purpose the strip support-

ing plate is provided on this marginal portion between the outer claws or prongs with a plurality of notches or recesses 55, thus forming passages between the marginal parts of the strip supporting plate and the inner side of the flange 97 on the gathering plate through which the air may pass from the exterior of the brush along the outer sides of the outermost strips, into the dust gathering chamber and through the openings of the gathering plate, as illustrated in Fig. 14.

In rear of the perforated gathering plate is arranged an equalizing chamber 56 and adjacent to the top wall of the enclosing casing is arranged a suction chamber 57 which is adapted to be connected with an air exhausting device of any suitable character. This suction chamber and the equalizing chamber are adapted to be connected and disconnected from each other about midway of the length of the same by means of a passage 58 connecting the central parts of these chambers and a valve 59 which is preferably constructed in the form of a plate and adapted to slide across the central part of this passage. The slide valve is provided with a port 60 adapted to be moved into and out of register with the passage 58. As shown in Fig. 2, the slide valve is drawn forwardly so that its solid or imperforate part extends across the valve passage, thereby disconnecting the suction chamber from the equalizing chamber and rendering the cleaning action of the brush inoperative. Upon moving the slide valve backwardly until its port 60 is in register with the passage 58, the suction chamber and equalizing chamber will be placed in communication with each other, so that the suction effect will cause the dust-laden air to be drawn through the brush into the gathering chamber and through the perforations and equalizing chamber into the suction chamber.

By arranging this valve passage midway, or substantially so, between the front and rear ends of the cleaning surface of the brush, the suction effect will be more nearly distributed so that all parts of the dust removing area of the brush will be acted upon and the dust effectively carried away. In order to still further equalize the suction effect over the entire area of the rubbing surface of the brush, those openings of the equalizing plate which are nearest to the valve passage 58 are made comparatively small while those arranged farther from this valve passage are made progressively larger in size, as indicated approximately in Fig. 4, whereby a substantially uniform distribution of the suction effect is obtained over the entire dust removing area of the brush, and cause all parts of the same to work with substantial uniformity.

The means for opening and closing the

suction controlling valve may be varied, but the same are preferably so organized that they may be operated by means of the same hand which manipulates the eraser during the cleaning operation by utilizing the closing action of the fingers of the operating hand while the same grasps the brush while cleaning the blackboard. For this purpose, the upper or handle portion of the brush is provided on its opposite longitudinal sides with two valve operating finger pieces 61, 61, which are preferably constructed of sheet metal and arranged in longitudinal recesses 62 formed in the adjacent parts of the top part of the sheet metal casing. These finger pieces have their outer edges connected by means of longitudinal hinges or pintles 63 to the top part of the brush handle, so that the inner parts of the same are capable of moving transversely relatively to the handle of the brush. The inward movement of these finger pieces toward each other is effected by the pressure of the fingers upon grasping the brush, and the outward movement of the same is effected by means of resilient elements, as will presently appear. This inward motion of the finger pieces toward each other is utilized to open the air valve 59 and the outward motion of these finger pieces serves to close this valve. The means whereby the opening and closing of the air valve is thus controlled may be constructed in various ways but the means for this purpose which are shown in the drawings as one suitable for this purpose have been found satisfactory in practice and therefore preferred. As there shown, these means are constructed as follows:

64, 64 represent two transversely swinging operating levers which are arranged within a valve chamber 65 located between the front part of the suction chamber and the corresponding part of the equalizing chamber, these levers being pivoted to each other and to the adjacent part of the partition between the suction chamber and the valve chamber by means of a rivet 66 having its axis arranged at right angles to the face of the cleaning surface of the brush. At their inner ends these valve levers are pivotally connected with shifting rods 67 which extend transversely outward through guide openings 68 formed in the adjacent parts of the handle and engage their outer ends with the inner surfaces of the finger pieces 61. Between the inner arms of the valve levers are arranged two toggle links 69, the inner ends of which are pivotally connected with each other and with the adjacent end of the air valve by means of a pin 70 while the outer extremities of these links are connected with the adjacent ends of the valve levers by means of the same pins 71 which connect the shifting rods with these levers, as shown in Fig. 3. These valve levers are turned in

the direction for causing their outer ends or arms to approach each other by means of springs 72 arranged in the front part of the valve chamber and each bearing at its inner 5 end against the front arm of one of the valve levers while its outer end engages with a seat 73 formed on the adjacent wall of the valve chamber, as best shown in Fig. 3.

In Figs. 2 and 3, the air valve is shown 10 in its closed position which it assumes when the grip upon the finger pieces is released and the cleaner is not in use. When it is desired to use the cleaner, the operator upon taking hold of the handle produces an in- 15 ward pressure of the fingers against both finger pieces which has the effect of pushing the rods 67 inwardly and causing the toggle links to fold toward each other, whereby the valve is caused to move from the front end of 20 the cleaner toward the rear end thereof, as shown in dotted lines in Fig. 3, and move its solid part away from the valve passage and its port 60 into register with said pas- 25 sage, so that now a suction is exerted upon the equalizing and gathering chambers and passages between the cleaning strips for drawing the dust-laden air through the same into the suction chamber. During this in- 30 ward movement of the finger pieces by the pressure of the fingers of the operator, the springs 72 are compressed, so that upon re- 35 leasing this pressure against the finger pieces, these springs owing to their resili- ence, immediately turn the valve levers in the reverse direction and cause the air valve to automatically close.

The suction chamber of the cleaning brush is connected by means of a flexible tube or 40 conduit 74 with an air exhausting device of any suitable character, so that the dust which is removed from the blackboard will be carried out of the class room and dis- 45 charged either to the external atmosphere or into some receptacle provided for that purpose. In order to permit of properly manipulating the eraser or cleaner without restraint from the air tube, the latter is connected with the rear end of the cleaner by means of a ball and socket joint which 50 in the preferred form shown in Figs. 1, 2, 3 and 9 comprises a spherical socket 75 ar- ranged at the rear end of the suction cham- ber and forming a continuation or exten- 55 sion thereof, and a spherical hollow knuckle 76 which turns in this socket and connects on its inner side therewith while its outer side is provided with a nozzle 77 which is connected with the suction line or tube 74.

It follows from this construction that the 60 eraser itself may be turned freely into any desired angle with reference to the conduit and thus enables the operator to clean the blackboard without any inconvenience. A packing 78 is preferably interposed between 65 the inner side of the socket and the exterior

of the knuckle which serves to prevent any leakage between the same and thus cause the suction effect upon the brush to be most effective for carrying away the dust. In using an eraser of this character on a black- 70 board 79, as shown in Fig. 16, the flexible air conduit which is connected with the brush is preferably extended through a slot or opening 80 in the rail or shelf 81 upon which the eraser ordinarily rests and the fixed end of this tube is connected with a main suction line or pipe 82 which is preferably arranged underneath this shelf or rail and leads to a vacuum pump or other 75 exhausting device by means of which the air is drawn through the brush and the conduits connected therewith for the purpose of discharging the dust removed by the brush to a space designed to receive the same. In order to prevent a short kink from being 80 produced in the flexible air tube 74 next to the main suction pipe 82, this part of the flexible tube is provided with a short sec- 85 tion of spring wire 83 which is coiled around the same and fastened to the adjacent fixed 90 part of the main suction line, as shown in Fig. 20.

In Fig. 16, two of such vacuum erasers are coupled with the same main air exhausting line, the right hand brush being shown in position for use and the left hand brush resting upon the rail when not in use. At a point convenient to both of these erasers, the rail of the blackboard is preferably pro- 95 vided with an auxiliary cleaning device with which the faces of the vacuum erasers may be engaged for the purpose of removing any particles of dust which may adhere thereto. The means for this purpose which are 100 shown in Figs. 16, 17, 18 and 19 are con- 105 structed as follows:

84 represents an auxiliary suction cham- ber arranged in an opening in the black- 110 board rail and having its top provided with perforations 85 and with brush bristles 86 while its bottom is connected by means 115 of a branch pipe 87 with the main exhaust line. This branch line contains a valve 88 which may be opened by means of a finger piece 89 guided on the underside of the blackboard rail and connected with a crank 90 on the stem of this valve and adapted to be shifted in a direction for closing this valve by means of a spring 91 interposed 120 between the shifting rod and the adjacent part of the auxiliary suction chamber, as shown in Figs. 17 and 19. Between the top and bottom of the auxiliary suction cham- 125 ber is arranged a distributing plate or equalizer 92 which is perforated and which serves to cause the suction which is created in the lower part of this chamber upon the opening of the valve 88 to be distributed substantially equally over the opening 85 and brush bristles on top of this chamber so 130

that upon placing the face of one of the erasers over the bristles and top openings of the auxiliary chamber, a substantially uniform air exhausting or suction effect will be produced upon the entire area of the eraser and thereby remove any dust particles which may adhere thereto. While pressing the hand operated eraser against the bristles of the auxiliary air chamber, this eraser is moved back and forth over the bristles and perforations of the auxiliary chamber, so as to loosen any particles of dust which may adhere to the strips of the eraser and thus aid in effecting a thorough cleaning of the latter.

This blackboard cleaning apparatus is very convenient in use and permits of effectively removing the dust from the blackboard with less effort than is required in the usual manner and at the same time insuring greater comfort for those occupying the class room as well as promoting the health of the same and maintaining the clothes, books, furnishings and furniture in a more sanitary condition.

Furthermore, this apparatus may be installed at comparatively low cost and without necessitating any material alterations in the structure of the blackboard and other equipment, and without detracting from the appearance of the same.

I claim as my invention:

1. A blackboard cleaner, comprising a plurality of strips of felt which are spaced apart to form air passages and each of which is provided on its top with a groove, and a supporting plate of metal having slots registering with said passages, beads engaging with said grooves, and claws on the edges of said slots and the walls of said beads and engaging with parts of the strip between the groove therein and the outer sides thereof.

2. A blackboard eraser, comprising a holder provided on its underside with a seat and in its upper part with a suction chamber, a brush having a support removably seated in said seat and having a plurality of felt strips and air passages between said strips communicating with said suction chamber, and means for detachably connecting said brush with said holder comprising a fixed hook mounted on one end of the holder and adapted to engage with the corresponding end of the brush, and a movable catch mounted on the other end of the holder and adapted to engage the same end of the brush.

3. A blackboard eraser comprising a holder provided on its underside with a seat and in its upper part with a suction chamber, a brush having a support removably seated in said seat and having a plurality of felt strips and air passages between said strips communicating with said suction

chamber, means for detachably connecting said brush with said holder comprising a fixed hook mounted on one end of the holder and adapted to engage with the corresponding end of the brush, a catch pivoted on the other end of the holder and having a hook adapted to engage the corresponding end of the brush, and a spring for yieldingly holding said catch in its operative position.

4. A blackboard eraser comprising a holder having a suction chamber in its upper part, a gathering chamber in its lower part, an air passage connecting the central part of said gathering chamber with said suction chamber, a valve for controlling the passage between said gathering and suction chambers, and a brush arranged below said gathering chamber and provided with air passages communicating with said gathering chamber.

5. A blackboard eraser comprising a holder having a suction chamber in its upper part, an equalizing chamber in its intermediate part which communicates with said suction chamber and has a perforated wall, and a brush arranged below said perforated wall and separated therefrom to form a gathering chamber therebetween and having air passages which communicate with said gathering chamber.

6. A blackboard eraser comprising a holder having a suction chamber in its upper part, an equalizing chamber in its intermediate part which communicates with said suction chamber and has a perforated wall, and a brush arranged below said perforated wall and separated therefrom to form a gathering chamber therebetween and having air passages which communicate with said gathering chamber, the perforations in said wall being comparatively small adjacent to the place of communication between said equalizing chamber and suction chamber and those perforations which are progressively farther from said place of communication being of correspondingly larger sizes.

7. A blackboard eraser comprising a holder having a suction chamber in its upper part, an equalizing chamber in its intermediate part which communicates with said suction chamber and has a perforated wall, and a brush arranged below said perforated wall and separated therefrom to form a gathering chamber therebetween and having air passages which communicate with said gathering chamber, said perforated wall being provided on its underside with projections which are engaged by said brush and which space the latter from said perforated wall.

8. A blackboard eraser comprising a holder having an inner perforated wall provided with a marginal depending flange, an

outer wall containing a suction chamber which communicates with said gathering chamber and has a depending marginal flange engaging the flange of said inner wall, a rubber bumper arranged between said flanges, a brush arranged within said flange and spaced apart from said inner wall to form a gathering chamber therebetween and having passages communicating 10 with said gathering chamber.

9. A blackboard eraser comprising a holder having a suction chamber, a brush mounted on the holder and having passages communicating with said suction chamber, 15 a slide valve controlling communication between said suction chamber and said brush passages, and means for actuating said valve comprising two operating levers pivotally mounted on said holder, springs engaging one end of said levers, shifting rods engaging the other ends of the levers, and means for transmitting the movement of 20 said levers to said valve.

10. A blackboard eraser comprising a holder having a suction chamber, a brush mounted on the holder and having passages 25

communicating with said suction chamber, a slide valve controlling communication between said suction chamber and said brush passages, and means for actuating said 30 valve comprising two operating levers pivotally mounted on said holder, springs engaging one end of said levers, shifting rods engaging the other ends of the levers, and toggle links connecting the other ends of 35 said levers with said slide.

11. A blackboard eraser comprising a holder having a suction chamber, a brush mounted on the holder and having passages 40 communicating with said suction chamber, a slide valve controlling communication between said suction chamber and said brush passages, and means for actuating said valve comprising two operating levers pivotally mounted on said holder, springs engaging one end of said levers, shifting rods 45 engaging the other ends of the levers, toggle links connecting the other ends of said levers with said slide, and finger pieces pivotally mounted on opposite sides of said 50 holder and engaging with said shifting rods.

WILLIAM J. LEARY.
